UNITED STATES PATENT OFFICE.

PHILIP T. HANDIGES, OF DETROIT, MICHIGAN.

CAR-COUPING:

SPECIFICATION forming part of Letters Patent No. 604,934, dated May 31, 1898.

Application filed November 19, 1897. Serial No. 659,089. (No model.)

To all whom it may concern:

Be it known that I, PHILIP T. HANDIGES, a citizen of the United States, residing at Detroit, county of Wayne, State of Michigan, have invented a certain new and useful Improvement in Car-Couplers; and I declare the following to be a full, clear, and exact description of the invention, such as will enable others skilled in the art to which it appertains to make and use the same, reference being had to the accompanying drawings, which form a part of this specification.

My invention has for its object certain new and useful improvements in car-couplers; and it consists of the construction, combination, and arrangement of devices hereinafter described and claimed, and illustrated in the accompanying drawings, in which—

Figure 1 is a vertical section showing parts in side elevation. Fig. 2 is a horizontal section on the line 2 2, Fig. 1. Fig. 3 is a similar section of parts of the device, but showing the locking-pin in locked position. Fig. 4 is a view in elevation of the locking-pin. Fig. 5 is a plan view of the same. Fig. 6 is a horizontal section on the line 6 6, Fig. 4. Fig. 7 is an inverted plan of the pin; and Fig. 8 is a side elevation of the device, showing a lever for withdrawing the pin.

More particularly my invention has for its object a car-coupler having an improved locking device whereby when the pin is withdrawn for uncoupling it will be brought into position, in the act of uncoupling, to automatically drop into locked position in the act of coupling adjacent cars, requiring no attendant to seat the pin in locked position.

Obviously a coupler provided with a locking device which only needs the attention of an attendant to throw the pin into unlocked position and which will automatically throw the locking device into locked position in the act of coupling cars without any further attention is a matter of great convenience and utility.

It is the purpose of my invention to provide a novel car-coupler with an improved locking device of superior efficiency and simplicity.

I carry out my invention as follows:

In the drawings, A represents a draw-bar provided with a head A' and a knuckle B, the head

being chambered to admit the adjacent portion of the knuckle, as shown. The draw-bar head and knuckle may be of ordinary construction, except as hereinafter stated, the head being formed with a vertical orifice extending therethrough (indicated at a) for the reception of a locking device or pin C. The head is formed with a ledge or flange projecting into the orifice a above the chamber in the head, as indicated in the drawings—for example, at a'. The drawings show this ledge or support upon the front wall of said orifice; but I do not limit myself to any given location of the support or ledge, as it might be formed on any side thereof, the action of the pin being made to conform to the location of the ledge.

Through the upper portion of the head adjacent to the orifice a and to one side of the locking-pin C, I locate a stop, preferably a pin D, the pin serving two functions—namely, to limit the upward movement of the locking-pin C and prevent its removal from the head, and also to form a fulcrum on which the locking-pin will be tilted when elevated. The locking-pin C may be lifted by any suitable device, as by a customary crank-arm E, connected therewith by a chain e, the crank-arm E provided with an extension projecting to the side of the car or otherwise, as may be desired, the lifting mechanism forming no special feature of my invention, as any desired lifting device may be employed to lift the locking-pin. The locking-pin is constructed on the side adjacent to the stop D with a shoulder c, and on the side adjacent to the ledge with a ledge or supporting shoulder c', the lower end C' of the pin projecting below the shoulder c', the shoulder at c' preferably extending diagonally across the pin, leaving the lower end C' of corresponding form. The shoulder c' is also preferably cut away on a bevel or slight arc on its inner surface, as indicated at c''. The locking-pin is preferably formed with right angles at one side thereof, the angles at the opposite side being on an obtuse angle and an acute angle, the right angles being indicated in Figs. 5 and 6 by the numerals 1 and 2, the acute angle being indicated by the numeral 3 and the obtuse angle by the numeral 4. I do not, however, limit myself solely to this form of construction.

The knuckle B is held in place in the coupler by the customary pivot-pin B', but the inner end of the knuckle is formed with a projecting shoulder (indicated at B²) projecting rearward and outward at one side the locking-pin in locked position, the head A' being recessed, as indicated at a², to permit the shoulder B² of the knuckle swinging in out of the way of the locking-pin in the act of coupling. The 5 knuckle adjacent to the locking-pin is cut away slightly at a suitable point (indicated, for example, in Figs. 2 and 3 at b) to contact with the cut-away surface at c² on the lower end C' of the locking-pin in the act of uncoupling, and thereby throw the pin down off the ledge a' and upon the upper surface of the shoulder B² of the knuckle.

In Fig. 1 the locking-pin C is shown in raised position ready for uncoupling. By reference to Fig. 8 it will readily be seen that when the pin C is lifted by the device E the shoulder c of the pin striking the stop D will cause the pin to be tilted, thereby engaging the shoulder c' of the pin upon the ledge a' of 25 the coupler-head. The attendant may then leave the coupling mechanism altogether. The further action of the locking device is as follows: In the act of uncoupling the adjacent edge, as the point b of the knuckle is in the 30 act of uncoupling and as the knuckle is being thrown open, will contact with the lower end c' of the locking-pin, which projects beneath the shoulder c'. As the knuckle is swung open this contact thereof with the lower end 35 of the pin will throw the shoulder c' of the locking-pin off the ledge a' of the coupler-head into the position indicated in dotted lines at the numeral 5, Fig. 1, the shoulder c' of the locking-pin resting upon the shoulder B² 40 of the knuckle and the lower end c' of the pin projecting downward alongside the adjacent face of the knuckle, permitting the cars to be uncoupled, while the locking-pin is also supported in position for coupling. When the 45 corresponding knuckle engages with the open knuckle B, it will of course throw the knuckle B back into locked position, and in so doing the rear end of said knuckle will ride out from under the shoulder c' of the locking-pin, 50 allowing said pin to automatically drop into locked position. (Indicated in Fig. 3.) The shoulder B² of the knuckle B is so formed, together with other parts of the device, that said shoulder will never ride outward from under 55 the shoulder c' of the locking-pin.

It will be evident that the parts which hold the locking-pin in suspended position are not movable parts, but that instead they always remain in fixed position. In the position indicated in Fig. 1 the locking-pin seats on the head and not on the knuckle.

This construction and arrangement of parts permits, as will be observed by reference to Fig. 3, a very effectual closing of the mouth 60 of the head of the draw-bar when the cars are coupled together, thereby excluding dirt, sleet, &c., from entering the mouth of the

draw-head and impeding the working of the mechanism.

The cut-away portion c² of the locking device and the cut-away portion b of the knuckle form cam-surfaces, whereby the locking device will be tripped off its fixed support on the opening movement of the knuckle.

What I claim as my invention is—

1. The combination with a coupler-head provided with a chamber and with an orifice extending through the head for the reception of a locking-pin, of a swinging knuckle, and a movable locking device mounted in said head projecting through the upper end of said orifice and formed with a supporting-shoulder toward its lower end, said head formed with a fixed support within said orifice to engage said shoulder and support the locking device in unlocked position, said pin in raised position being lifted up so that the projecting shoulder thereon engages on said fixed support above the chamber of the draw-head, for the purpose described.

2. The combination with a coupler-head provided with a chamber to receive the knuckle, and with an orifice therethrough to receive a locking-pin having a fixed support therewithin above said chamber, of a swinging knuckle, a vertically-movable locking-pin passing through said orifice in the head provided with a supporting-shoulder toward its lower end, a lifting device connected with the upper end of said pin, and a fulcrum at 100 one side the locking-pin above said chamber to tilt the locking device when in raised position and seat the supporting-shoulder of the pin upon said fixed support, whereby the pin may be automatically held in an uncoupled 105 position, said pin in raised position being lifted up so that the projecting shoulder thereon engages on said fixed support above the chamber of the draw-head, substantially as set forth.

3. The combination with a coupler-head formed with a chamber and with an opening through the head, of a swinging knuckle, and a vertically-movable locking-pin mounted in said orifice and projecting through the upper 115 end thereof, said head constructed with a fixed support projecting inward within said opening, and said locking-pin constructed with a supporting-shoulder toward its lower end to engage said ledge, said pin in raised 120 position being lifted up so that the projecting shoulder thereon engages on said fixed support above the chamber of the draw-head, substantially as set forth.

4. The combination of a coupler-head provided with an orifice therethrough for the reception of a locking-pin and having a fixed support within said orifice, of a swinging knuckle, and a locking-pin provided with a supporting-shoulder toward its lower end to 130 engage the support within said orifice to support the pin in raised position upon the fixed support within said orifice in position for uncoupling, the inner end of said knuckle by

its opening movement tripping the locking device from off said support and throwing said supporting-shoulder upon the upper surface of the knuckle into position to drop into 5 locked position at the closing movement of the knuckle, for the purpose set forth.

5. The combination with a chambered coupler-head, formed with an orifice extending therethrough to receive a locking device, of a 10 swinging knuckle, a vertically-movable locking-pin passing through said orifice and provided with a supporting-shoulder toward its lower end, and a fulcrum at the rear of the locking-pin above the chamber in said head, 15 said head formed with a fixed support projecting inward on the front wall of said orifice intermediate the ends of said opening to engage said shoulder and support said pin, said pin in raised position being lifted up so 20 that the projecting shoulder thereon engages on said fixed support above the chamber of the draw-head, for the purpose described.

6. The combination with a coupler-head provided with a chamber and with an opening 25 through the head to receive a locking-pin, of a swinging knuckle, a vertically-movable locking-pin provided with a supporting-shoulder on one side thereof toward its lower end, and with an additional shoulder on the opposite side thereof, a fulcrum at one side the locking device above the chamber in the head, and a fixed support on the opposite side the locking device within said opening above the chamber in the head to engage the corresponding 30 shoulder of the locking device and support the pin in unlocked position, said pin in raised position being lifted up so that the projecting shoulder thereon engages on said fixed support above the chamber of the draw-head, 35 substantially as set forth.

7. The combination with a coupler-head provided with an orifice therethrough for the reception of a locking-pin and having a fixed support within said orifice, of a swinging 40 knuckle provided with a shoulder at its inner end, and a locking device provided with a supporting-shoulder toward its lower end to engage said fixed support in position for uncoupling, said locking device projecting below 45 said supporting-shoulder, the inner end of said knuckle by its opening movement tripping the locking device and throwing the supporting-shoulder off said fixed support and upon the shoulder of the knuckle into position 50 to permit the locking device to drop into locked position at the closing movement of the knuckle, for the purpose set forth.

8. The combination with a chambered coupler-head provided with an orifice therethrough 55 for the reception of a locking-pin and having a fixed support within said orifice above the chamber of the head, of a swinging knuckle provided with a shoulder projecting inward and outward at its inner end, and a locking 60 device provided with a supporting-shoulder toward its lower end to engage said fixed sup-

port in position for uncoupling, and having its lower end projecting below said supporting-shoulder, the inner end of said knuckle by its opening movement contacting with the 65 lower end of the locking device and tripping the locking device throwing the supporting-shoulder off from said fixed support and upon the upper face of the shoulder of the knuckle into position to permit said latter shoulder riding out from in under said supporting-shoulder in the closing movement of the knuckle, whereby the locking device may drop into 70 locked position in front of the shoulder of the knuckle, substantially as set forth.

9. The combination with a coupler-head provided with a chamber and with an opening through the head to receive a locking device, and with a fixed support within said opening, of a swinging knuckle, a vertically-movable locking device in said opening provided with a supporting-shoulder toward its lower end to seat upon said fixed support in uncoupled position, a fulcrum at one side the locking device serving as a stop to limit the 80 upward movement of the locking-pin, and also serving to seat the supporting-shoulder of the locking device upon said fixed support in uncoupled position, said pin in raised position being lifted up so that the projecting 85 shoulder thereon engages on said fixed support above the chamber of the draw-head, substantially as set forth.

10. The combination with a coupler-head provided with an orifice extending therethrough for the reception of a locking-pin, and constructed with a fixed support within said orifice, of a swinging knuckle, and a movable locking-pin mounted in said head projecting through the upper end of said orifice, said locking-pin formed with a supporting-shoulder c' to seat upon said fixed support, and with a portion C' at the lower end of the pin projecting downward below said supporting-shoulder, said knuckle formed 100 with a shoulder B^2 , said latter shoulder by the opening movement of the knuckle contacting with the portion C' of said pin to trip the pin from off said fixed support and throw the supporting-shoulder of the pin upon the 105 upper surface of the shoulder of the knuckle into position to drop into locked position at the closing movement of the knuckle, substantially as set forth.

11. The combination with a coupler-head 110 provided with an orifice extending therethrough for the reception of a locking-pin, and formed with a fixed support within said orifice, of a swinging knuckle, and a movable locking-pin mounted in said head projecting 115 through the upper end of said orifice, said locking-pin formed with a supporting-shoulder c' , with a portion C' projecting below said supporting-shoulder, and with a cut-away portion c^2 , said knuckle formed with a shoulder B^2 , and with a cut-away portion b to contact 120 with the cut-away portion c^2 of the pin in the 125

130

opening movement of the knuckle to trip the locking device from off the fixed support and throw the supporting-shoulder of the pin upon the upper surface of the shoulder of the knuckle into position to drop into locked position at the closing movement of the knuckle, for the purpose set forth.

In testimony whereof I sign this specification in the presence of two witnesses.

PHILIP T. HANIGES.
